UNITED STATES PATENT OFFICE.

FREDERICK W. MAGEE, OF LONDON, ONTARIO, CANADA, ASSIGNOR OF ONE-HALF TO
THOMAS W. BAKER, OF LONDON, ONTARIO, CANADA.

DESIGN FOR A GAS-LAMP BODY.

42,365.

Specification for Design.

Patented Mar. 26, 1912.

Application filed September 9, 1910. Serial No. 581,339. Term of patent 14 years.

To all whom it may concern:

Be it known that I, FREDERICK W. MAGEE, a subject of the King of Great Britain, residing at the city of London, in the county of Middlesex, in the Province of Ontario, Canada, have invented a new, original, and ornamental Design for Gas-Lamp Bodies, of which the following is a specification, reference being had to the accompanying drawings, forming part thereof, in which—

Figure 1 is a top view of the body of an inverted arc gas lamp embodying my design. Fig. 2 is a side view of same. Fig. 3 is another view of same looking at it from the underside.

The central portion of the body is in the form of a cylindrical member 5 connected near its upper end by circular necks 6 with the upper faces of elongated cylindrical members 7 which lie in planes parallel to

the necks 6 so as to project radially from the central portion 5, and are so disposed with relation to said body-portion 5 that their lower faces are in substantially the same plane as the lower end of said body 5. Extending upwardly from the necks 6 are tubular-shaped parts 8, and on the upper faces of the members 7, projecting beyond the outer extremities of the necks 6 are tubular parts 9.

I claim—

The ornamental design for a gas lamp body as shown and described.

In testimony whereof, I have signed in the presence of the two undersigned witnesses.

FREDERICK W. MAGEE.

Witnesses:

P. J. EDMUNDS,
S. HARDY.
